UNITED STATES PATENT OFFICE.

JOHN D. MURRAY, OF SAN FRANCISCO, CALIFORNIA.

NOZZLE TIP.

Application filed November 19, 1923. Serial No. 675,511.

To all whom it may concern:

Be it known that I, JOHN D. MURRAY, a citizen of the United States, residing at city and county of San Francisco and State 5 of California, have invented certain new and useful Improvements in Nozzle Tips, of which the following is a specification.

The present invention relates to a spray tip designed for use generally where it is 10 desired to spray a mixture under pressure either in the form of a flat stream or in a jet.

The invention relates particularly to that type of spray illustrated in my co-pending 15 application #599,994, filed Nov. 10, 1922 and has for its objects to provide a tip having a longer life and adapted for more universal use than that illustrated in the disclosure of the application.

20 The objects of the present invention are to provide within the bore through which the fluid passes under pressure freely mountable fluid-actuated means preferably spherical in form against which the impact stream 25 strikes on its passage through the bore; to provide a slotted tip for removable positioning over the cylindrical discharge bore when it is desired to convert the jet stream issuing from the bore into a flat stream; and 30 in the broad aspects of the invention provide means for breaking up a stream flow through a nozzle into a fine spray overcoming the liability of the stream flow under pressure of cutting out the nozzle.

35 With the above mentioned and other objects in view, the invention consists in the novel construction and combination of parts hereinafter described, illustrated in the accompanying drawings, and set forth in the 40 claims hereto appended, it being understood that various changes in the form, proportion, size and minor details of construction within the scope of the claims may be resorted to without departing from the spirit 45 or sacrificing any of the advantages of the invention.

Fig. 1 is a view in side elevation of the preferred embodiment of my invention illustrating the base and retaining collar in 50 longitudinal section.

Fig. 2 is a longitudinal sectional view of the preferred embodiment of my invention with the retaining collar removed and illustrating the ball atomizing member in 55 the discharge bore.

Fig. 3 is a transverse sectional view taken on line 3-3 of Fig. 2.

Fig. 4 is a view in end elevation of the discharge tip.

Fig. 5 is a longitudinal sectional view 60 with the body and tip removed from the base and

Fig. 6 is a view of the body with the tip removed illustrating the use of the body when a jet stream is desired. 65

In the drawings forming a part of the application and illustrating the preferred embodiment of my invention, the numeral 1 indicates a tubular base having a peripherally threaded end 2 and the terminal end 70 of the base is formed with a body receiving seat 3. Removably positioned within the seat 3 is the cylindrical end of a tubular body 4 having a tubular reduced discharge end 5, the body 4 being provided with an 75 inlet bore 6 and the discharge end being provided with a discharge bore 7 of a diameter greater than that of the inlet bore 6. The sides of the bores are preferably parallel and within the discharge bore is loosely 80 mounted a ball or spherical atomizing member 8 of a diameter greater than that of the inlet bore but less than the diameter of the discharge bore. The member 8 is loosely confined within the bore between the transversely disposed cylindrical stop pins 9 extending across the bore adjacent its opposite ends. It will be observed that a fluid stream flow under pressure entering the discharge bore will stroke the member 8 and 85 will be deflected by its surface toward the side walls of the bore and the action of the stream flow in forcing the member 8 against the outer member 9 will cause the member to move rapidly within its confined space 90 and not assume any one set position, thus insuring breaking up of the stream flow prior to its passing from the discharge end of the bore. When a jet stream is desired and the body 4 is positioned within the seat 95 3 and a threaded collar is positioned over the discharge end of the body and is threaded onto the base 1 until the flange 10 of the collar engages the flange 11 of the base to tightly retain the base in its seat. 100

To provide a means for converting the atomized material into a flat stream I removably position over the contracted end 5 of the base, a tip 12 transversely slotted at 13 and of the conventional gas tip type, 110

- the same being provided on its under side with a domed chamber 14 and registering with the discharge end of the discharge bore 7. The base of the tip is flanged as at 15 5 and when the same is positioned on the reduced end 5 of the body 4 it is retained thereon by the collar positioned thereover and threaded onto the base 1 until its flange 10 engages the flange 15 of the tip.
- 10 I have provided by this construction a nozzle tip adapted for universal use such as paint spraying, garden hose work, irrigation or, in fact, any use where a fluid stream under pressure is desired to be projected.
- 15 I claim:
1. A discharge nozzle comprising a body provided with cylindrical axially aligned inlet and discharge bores having parallel walls, the discharge bore being of greater 20 diameter than the inlet bore, and a spherical member loosely held within said discharge bore at a point inwardly from the discharge end of the discharge bore for breaking up the stream flow passing therethrough.
  2. A discharge nozzle comprising a body provided with axially aligned inlet and discharge bores, the discharge bore being of greater diameter than the inlet bore, a pair of stop pins extending transversely of the 30 discharge bore and disposed in spaced relation, and a ball loosely confined within said bore between said stop pins.
  3. A discharge nozzle comprising a body provided with axially aligned inlet and discharge bores, the discharge bore being of greater diameter than the inlet bore, a ball 35 loosely held within the discharge bore for breaking up the stream flow passing there-
- through and a slotted tip over the end of said discharge bore. 40
4. A discharge nozzle comprising a body provided with axially aligned inlet and discharge bores, the discharge bore being of greater diameter than the inlet bore, a ball loosely held within the discharge bore for 45 breaking up the stream flow passing therethrough, a transversely slotted tip removably positioned over the discharge end of said discharge bore, and means for retaining the tip in position thereon. 50
5. A discharge nozzle comprising a body provided with axially aligned inlet and discharge bores, the discharge bore being of greater diameter than the inlet bore, a ball loosely held within the discharge bore for 55 breaking up the stream flow passing therethrough, a transversely slotted tip removably positioned over the discharge end of said discharge bore, a base for receiving said body, and a threaded collar bearing on said tip and threadably engaging the base for retaining the tip on the body and the body removably positioned in the base. 60
6. A discharge nozzle comprising a body provided with axially aligned inlet and discharge bores, one of a diameter larger than the other, a ball within one of said bores for 65 breaking up the stream flow passing therethrough, and a pair of cylindrical rods disposed transversely across the bore containing 70 the ball for confining the ball therein, said ball being of a diameter less than that of its receiving bore.

In testimony whereof I have signed my name to this specification.

JOHN D. MURRAY.
